UNITED STATES PATENT OFFICE.

WILLIAM BLOOMBERG, OF NEW YORK, N. Y.

GARBAGE-PAIL.

No. 824,775.

Specification of Letters Patent.

Patented July 3, 1906.

Application filed March 9, 1905. Serial No. 249,297.

To all whom it may concern:

Be it known that I, WILLIAM BLOOMBERG,
a citizen of the United States, residing in
Brooklyn borough, city of New York, in the
county of Kings and State of New York, have
invented certain new and useful Improve-
ments in Garbage-Pails, of which the follow-
ing is a specification.

This invention relates to garbage cans or pails. It often happens that pails set out upon the sidewalk to be collected are allowed to remain one or more days before the garbage-collector makes his rounds, and through accidents the pails are frequently upset and their contents become distributed about the neighborhood to the annoyance of the public. They are often upset by large dogs, and even if not upset the animals frequently succeed in transferring a considerable portion of the garbage from the pails to the sidewalk. To avoid the attacks of animals, it has been attempted to use loose covers; but these usually are removed by the animals and lost and afford no protection. If the covers are made tight fitting, so that animals cannot remove them, it soon happens that owing to the rough usage of the pails at the hands of the garbage-collectors the pails and covers become misshapen and no longer fit each other. Another serious objection to the use of covers is that in case the pail is heaped with garbage, as is often the case, the covers cannot be placed upon them at all.

35 The object of my invention is to overcome these and other objections, and to that end I provide for the garbage-pail a cover having a deep skirt which telescopes way down over the body of the pail and is of such depth that even after the pail has been heaped up to the 40 highest possible limit the bottom of the skirt still has a sufficiently full hold around the body of the pail. Moreover, the cover cannot be removed by animals nor by being tipped over, and all of the objections above 45 noted are overcome.

In the accompanying drawings, Figure 1 is a sectional view of a garbage-pail provided with my improvements, the pail being shown heaped up with garbage to illustrate that the cover still has ample hold upon the pail. Fig. 2 is an elevation of the pail and cover. Fig. 3 is an elevation of the cover.

A garbage-pail usually consists of a cylindrical body 1, having a bottom 2. To the opposite sides of the pail are fixed ears 3. To these ears I attach the ends of a bail 4.

The cover comprises a top 5 and a skirt 6 of very great depth and fitting loosely over the pail. This skirt extends down far beyond the ears 3, and I provide in the skirt opposite recesses 7, which may be wide enough to slide readily up and down past the ears, while their bottoms are flared out, as at 8, to enable the cover to be readily directed down past said ears. To further facilitate the placing of the cover upon the pail, I provide upon the top thereof a handle 9, which is in line with said recesses, so that the user by setting said handle in line with the ears 3 will find that the cover will slip down readily upon the pail. A wire 10 runs along the edges of the cover to stiffen the same, the edges of the cover being rolled over said wire. The latter is continuous around the under edge of the cover following the edges of the recesses, which are also rolled over the wire. The cover is preferably made of a single piece of sheet metal, including both the body and the skirt, although within the scope of the invention the top may be made in one piece and the skirt in one or more pieces and attached to the top. Preferably the skirt has a straight cylindrical form, so that it will always fit upon the pail, even when the latter is first heaped up with garbage, as at A, Fig. 1.

One of the advantages of the invention lies in the difficulty of removing the cover from the pail. The cover must be drawn straight up in order to be removed. This difficulty is no objection to the user; but it 90 absolutely prevents accidental removal of the cover by animals. Indeed, if the pail is accidentally upset and rolled about the cover does not come off, and hence the danger of the garbage being spread about is eliminated. 95 It will be seen that even when the pail is heaped up to the utmost limit, as at Fig. 1, the skirt of the cover still has a full and effective hold upon the pail. The bail 4 is made of relatively great height to clear the cover and handle when in the Fig. 1 position. 100

Other variations may be resorted to within the scope of my invention.

Having thus described my invention, I claim—

1. A garbage-pail having eyes upon its opposite sides, a bail attached to said eyes, and a cover formed with a loosely-fitting skirt of such great depth as to extend far below said eyes; said skirt having openings or cut-aways upon its opposite sides to receive said eyes; said recesses coöoperating with the

eyes to prevent rotation of the cover, so that it is impossible for the cover to be worked off by the rolling about of the pail; the lower edges of the cover and the edges of the eyes 5 being rolled over so as to stiffen the skirt.

2. A garbage-pail having eyes upon its opposite sides, a bail attached to said eyes, and a cover having a skirt of great depth which telescopes down around the sides of said pail 10 below said eyes; said cover having opposite recesses which receive said eyes, and a stiffening-wire extending along the lower edges of the cover and around the edges of said eyes; the edges of the cover rolled over said wire.

15 3. A garbage-pail having eyes upon its opposite sides, and a bail attached to said eyes, and a cover having a cylindrical skirt of great depth which telescopes down around the sides of said pail below said eyes, said 20 cover having opposite recesses which receive said eyes, and a stiffening-wire extending around the lower edges of the cover and

also along the edges of said recesses; the latter flaring at their lower portions so as to direct the cover over said eyes, and the edges 25 of the cover rolled over said wire.

4. A garbage-pail having eyes upon its opposite sides, and a bail attached to said eyes, and a cover having a cylindrical skirt of great depth which telescopes down around the sides of said pail below said eyes; said cover having opposite recesses which receive said eyes, and a stiffening-wire extending around the lower edges of the cover and also along the edges of said recesses; the latter flaring at 30 their lower portions so as to direct the cover over said eyes and the edges of the cover rolled over said wire; said cover having a handle thereon which extends across the cover in line with said recesses.

WILLIAM BLOOMBERG.
